WILLIAM C. BUNDSCUH, OF IRVINGTON, NEW JERSEY, ASSIGNOR TO HERMAN JELINCK, OF IRVINGTON, NEW JERSEY.

CUTTER-BAR FOR PLANING-MACHINES.

No. 919,287.

Specification of Letters Patent. Patented April 20, 1909.

Application filed May 4, 1908. Serial No. 430,635.

To all whom it may concern:

Be it known that I, WILLIAM C. BUNDSCUH, a citizen of the United States, residing at Irvington, in the county of Essex and 5 State of New Jersey, have invented certain new and useful Improvements in Cutter-Bars for Planing-Machines; and I do hereby declare the following to be a full, clear, and exact description of the invention, such as 10 will enable others skilled in the art to which it appertains to make and use the same, reference being had to the accompanying drawings, and to figures of reference marked thereon, which form a part of this specification. 15

This invention relates to an improved cutter-block for planers or joiners, and consists in a block with knife or planing edges on its blades, which cutting edges project 20 slightly beyond a substantially circular periphery, this periphery being the result of placing cheek-pieces on an old-style cutter-block. The cheek-pieces on two opposite sides are used to secure the blades of the 25 cutter-block, and the cheek-pieces on the remaining two sides are made with chip-grooves adjacent to the cutting edges of the blades.

The cutter-block previously used is of 30 course not the novel feature of this invention, but the cheek-pieces and the means for clamping and adjusting the blades are new.

The invention is illustrated in the accompanying drawing, in which—

35 Figure 1 is a side view of my improved cutter broken away to show the cutter-block. Fig. 2 is an end view of the cutter with one cheek-piece shown in section. Fig. 3 is an end view of the cutter-block, and 40 Fig. 4 is a view of a tool used for fastening and adjusting the blades.

I employ a cutter-block 10 which, as heretofore made, has the curved raised edges 11 adjacent to the blades 12 and forming chip-grooves. The cutter-block is suitably secured to a shaft 13 and planes the under side of a board passing the opening 15 in the table 14, as will be evident. I remove the raised edges 11 from an old cutter-block or 45 make a new block without them, and I insert in each of the bolt grooves 16 a square headed bolt 17 which projects from the block and into a cheek-piece. On each of the opposite

sides of the block 10 I secure a cheek-piece 18 cut away its entire length and part of its 55 width, to receive a blade 19 having the cutting edge projecting slightly beyond the edge of the cheek-piece which has its outer edge concentric to the shaft 13, of the cutter-block, and with the inner edge of the opening 15. 60 The blade 19 is thus clamped in place when the nut 20 is screwed down in the recess 21. The nut 20 has perforations 22 for receiving a 65 spanner wrench 23, the other end 24 of the wrench being utilized to fit in the slots 25, arranged in each cheek-piece 18, to act on the back edge of either of the blades 19 to adjust them prior to their being fastened. The other cheek-pieces 26 fit in the faces of the block 10 between the slots 25 and the blades 70 19, and also have their outer surface concentric to the shaft 13 of the block 10. Each cheek-piece has a chip-groove 27 on its edge adjacent to a blade 19.

The advantages of this cutter device are 75 many, since the chance of the operator getting fingers in the opening 15 and having them cut off is not present, since the opening 15 is nearly closed and the entry of an element is limited. In the old way the opening 80 15 is open and the chances of accident are correspondingly greater. The shock on planks etc., being fed to the machine, is slight compared to the first contact of the blades 12 in an old-style of machine. The 85 concentric periphery of the improved cutter prevents material on the opening 15 from sagging and presenting an excess of material to the knives or blades.

Having thus described my invention, what 90 I claim is:—

A cutter comprising a cutter-block rectangular in cross-section and having longitudinally arranged bolt grooves in its faces, cheek-pieces with outside surfaces concentric to the center of the block secured to the sides of the block, bolts having heads in the grooves, perforated nuts set in recesses in the cheek-pieces to provide a substantially flush surface and adapted to screw on the bolts to 95 secure the cheek-pieces to the cutter-block, blades secured between oppositely arranged cheek-pieces and the cutter-block, the cheek-pieces securing the blades having a series of separated unobstructed grooves arranged 100 alternately with the nuts in the grooves ex-

tending from the blades to the back edge of the cheek-pieces, the grooves being devoid of permanent adjusting means, and adapted to receive a handle of the spanner for adjusting the nuts for the purpose of adjusting the blades.

In testimony that I claim the foregoing, I

have hereunto set my hand this 2nd day of May, 1908.

WILLIAM C. BUNDSCUH.
